UNITED STATES PATENT OFFICE.

ABBOT AUGUSTUS LOW, OF HORSESHOE, NEW YORK.

FUEL-SUPPLY MEANS FOR EXPLOSIVE-ENGINES.

SPECIFICATION forming part of Letters Patent No. 767,483, dated August 16, 1904.

Application filed August 5, 1903. Serial No. 168,255. (No model.)

To all whom it may concern:

Be it known that I, ABBOT AUGUSTUS LOW, a citizen of the United States, residing at Horseshoe, St. Lawrence county, and State 5 of New York, have invented certain new and useful Improvements in Fuel-Supply Means for Explosive-Engines, of which the following is a specification sufficient to enable others skilled in the art to which the invention applies 10 pertains to make and use the same.

My present invention relates to explosive-engines in which alcohol-vapor is used on account of its comparatively low explosive temperature either to effect the starting of the 15 engine or permanently in connection with the usual charge of hydrocarbon explosive; and the novelty resides in the peculiar construction and arrangement of parts, all as more fully hereinafter described and claimed.

20 In the accompanying drawings, Figure 1 is a diagrammatic representation of the parts essential in carrying out my invention. Fig. 2 is a vertical section through the alcohol drip-cup.

25 S is the cylinder of the engine, and P the piston reciprocating therein.

C is the combustion-chamber, provided with the usual electric sparking attachment E for effecting the preliminary explosions of the 30 engine.

I is an injector of well-known construction for introducing hydrocarbon vapor into the combustion-chamber C after the engine has been started by the explosion of alcohol-vapor therein, as hereinafter set forth, *i* being a valve in the supply-pipe for controlling the supply of hydrocarbon.

35 A is an alcohol drip-cup (shown in section at A' of the drawings) provided with a needle-valve *a*, by which the drip is controlled.

B is a stand-pipe, upon the upper end of which the drip-cup A is mounted, perforated inclined partitions *b* being interposed in the path of the alcohol to insure the spread and 45 distribution of the latter. The stand-pipe B

is connected by a lateral branch B' with the automatic inlet-valve V, opening into the passage *v*, through which the vapor passes into the cylinder S.

*b*² represents a series of perforated trays 50 arranged in the lower part of the stand-pipe B for admitting air thereto when desired, a valve or damper *b*³ being provided, by means of which the lower portion of the stand-pipe may be closed.

R is a reservoir containing compressed air, which is supplied thereto by means of a pump R' or equivalent means. A supply-pipe *r* extends from the reservoir R and terminates in a nozzle *r'*, which projects into the stand-pipe 60 B opposite to the lateral passage B', a valve *r*² being interposed in the pipe for the purpose of shutting off or regulating the supply of air under pressure.

The operation of the apparatus is substantially the same as set forth in application Serial No. 155,825, filed May 6, 1903, with this exception, that the compressed air takes up and completely atomizes the alcohol prior to its introduction into the combustion-chamber, 65 at the same time supplying it with an excess of oxygen, so that its combustion within the engine is insured. After the engine has been started by means of the combined charge of fresh air and alcohol the hydrocarbon-injector I may be started and the supply of alcohol 70 shut off, if desired, or both the alcohol and hydrocarbon charges may be used simultaneously, if preferred. When the alcohol is shut off, the damper *b*³ is opened, as well as an auxiliary damper *b*⁴ in the stand-pipe opposite the lateral passage B', thereby admitting air to the combustion-chamber to facilitate the combustion of the hydrocarbon introduced 75 through the injector I.

In order to increase the vaporizing effect of the compressed air as related to the alcohol and also increase the rapidity of combustion, I in some cases heat the compressed air prior to its introduction into the stand-pipe B, and 80 85 90

this may be accomplished by any convenient or well-known means, as by a lamp L, situated under the reservoir R.

What I claim as my invention, and desire to 5 secure by Letters Patent, is—

The combination, in an explosive-engine, of means auxiliary to the main fuel-supply, for supplying alcohol, means for insuring its spread and distribution, means for introducing air under pressure at a point intersecting

the flow of the alcohol prior to its admission to the combustion-chamber, and means for admitting air in the direction opposite to the flow of the alcohol and at right angles to the introduction of the compressed air.

ABBOT AUGUSTUS LOW.
